CIRCUIT INTERRUPTING APPARATUS

George F. McMahon, Chicago, Ill., assignor to
 Schweizer & Conrad, Inc., Chicago, Ill., a corporation of Delaware

Application June 14, 1940, Serial No. 340,423

25 Claims. (Cl. 200—120)

This invention relates, generally, to circuit interrupters and it has particular relation to the prevention of the expulsion of combustible material from a circuit interrupter on operation thereof.

When an arc is formed between a pair of terminals connected to a suitable source of electrical energy, a certain amount of metal is vaporized and new metallic compounds are formed as the result of chemical combination of the surrounding air or arc extinguishing materials. The origin of this metal is the terminals themselves, or, if they are connected by metallic fusible means, then the vaporized metal comes from both the terminals and the fusible means. The arc extinguishing chemicals are generally in close proximity to the fusible means and terminals and they are vaporized and decomposed by the heat of the arc.

In the normal state at room temperature the metal which is vaporized by the heat of the arc is usually considered as being nonmagnetic. Often the magnetic susceptibility of some metals changes upon vaporization due to increase in temperature, an increase being noted in some special cases as with silver. In the newly formed metallic compounds the magnetic susceptibility of some is sometimes greater than that of the original pure metal vapor. Ordinarily the terminals are formed of copper, aluminum or brass. If the terminals are connected by fusible means, it usually takes the form of silver, tin, lead, zinc or alloys thereof. At the temperature of the arc, the vaporized metal takes the form of ionized metallic particles or metallic compounds and it has been found that they possess magnetic properties and that their positions can be influenced or controlled by a strong magnetic field.

In order to extinguish the arc between the terminals resort is had to various means. The terminals can be relatively moved apart so as to extend the arc so far that it cannot maintain itself. Arc extinguishing materials in either the liquid or the solid form or both are so positioned relatively to the arc that an arc extinguishing medium in the form of gas or vapor is evolved therefrom by the heat of the arc which assists in extinguishing the same. Gas, such as air, under pressure may be blown across the arc to extinguish it. Combinations of these means are also employed. Generally a blast results which sweeps out the space between the terminals so as to prevent restriking of the arc once it has been extinguished.

The blast which results from the sweeping out 55

action of course contains the metallic particles as well as the arc extinguishing medium, newly formed compounds, and other gases. It is customary, in the event that relatively high pressure results from the arc blast, to exhaust it to the atmosphere. As soon as the particles are exposed to the air, they support combustion and a flame is the immediate result as oxidation progresses. Such a flame is often observed in the products of the arc that form the blast when the latter encounters the air, even after the arc between the terminals itself has been extinguished. Thus, after the circuit has been satisfactorily interrupted, there is still the possibility, and it often happens, that a quantity of flame will appear outside of the circuit interrupter in the cloud of other materials making up the arc blast.

Flame, since it contains ionized or electrically charged particles, is a good conductor of electricity. If it comes into proximity with a high voltage circuit, it may either cause it to be grounded or to be short circuited on another conductor. It is to the prevention of such a flame that the present invention is directed.

An object of this invention is to prevent the occurrence of a flame in the arc blast outside of a circuit interrupter.

Another object of this invention is to remove from the arc blast particles that support combustion on exposure to the air.

A further object of this invention is to remove the particles from the arc blast by magnetic means.

It is also an object of this invention to sweep out the space between a pair of terminals between which an arc is formed by a blast which carries with it ionized and unionized particles, to confine the blast during a portion of its travel and while thus confined to remove or influence the otherwise normal path of travel of the particles contained therein so that they are not permitted to contact the air.

Another object of the invention is to influence the path of travel of the particles by magnetic means while the blast is confined under pressure.

Other objects of this invention will, in part, be obvious and in part appear hereinafter.

For a more complete understanding of the nature and scope of this invention, reference may be had to the following detailed description taken in connection with the accompanying drawings, in which:

Figure 1 is a longitudinal sectional view of one embodiment of the invention, the upper and low-

er permanent magnets being shown in elevation;

Figure 2 is a detail sectional view taken along the line 2—2 of Figure 1;

Figures 3A and 3B taken together constitute a longitudinal sectional view of another embodiment of the invention;

Figure 4 is a detail sectional view taken along the line 4—4 of Figure 3A;

Figure 5 is a perspective view of the permanent magnets and holder therefor that are employed in the embodiments of the invention shown in Figures 3A and 3B;

Figure 6 is a longitudinal sectional view of still another embodiment of the invention; and

Figure 7 is a detail sectional view taken along the line 7—7 of Figure 6.

Referring now particularly to Figure 1 of the drawings, it will be observed that the reference character 10 designates, generally, a liquid type fuse device such as is shown in Conrad Patent No. 2,091,430. It is provided with a tubular insulating housing 11 that is preferably formed of glass and is filled with a liquid 12 to the level indicated at 13. The liquid 12 may be as disclosed in McMahon Patent No. 2,077,429. In general it comprises a halogenated hydrocarbon. In particular it may comprise a chlorinated hydrocarbon.

The fuse device 10 is provided with a pair of separable terminals 14 and 15, the terminal 14 being stationarily mounted, as will hereinafter appear, and the terminal 15 being arranged to be moved away from the stationary terminal 14 in order to elongate the arc formed therebetween to extinguish the same as will be readily understood. The terminals 14 and 15 are interconnected by a fusible element 16, preferably in the form of silver wire and by a strain element 17 comprising a high strength wire such as a nickel chromium alloy wire. Around the fusible and strain elements 16 and 17 there is provided an arcing chamber 18 of insulating material through which the liquid 12 is forced to flow by means of a liquid director 19 that is carried by the movable terminal 15. The terminal 15 carrying the liquid director 19 is arranged to be retracted by a coil tension spring 20 when the fusible and strain elements 16 and 17 blow. The terminal 15 is connected by means of flexible conductors 21 to a terminal, not shown, at the lower end of the housing or fuse tube 11.

The arcing chamber 18 is centrally mounted in the upper end of the housing 11 by means of an insulating washer 24 that is threaded, as shown, into a metallic terminal 25 that is secured to the upper end of the housing 11 in what is now a conventional manner. The terminal 25 is provided with an upwardly facing shoulder 26 on which rest the downwardly projecting fingers of a metallic spider 27 which supports the stationary terminal 14 in operative position.

It will be observed that the terminal 25 is provided with a cylindrical extension 28 that is closed at its upper end by a vent cap 29, which is arranged to be blown off in the event that sufficient pressure is developed within the extension 28 on operation of the fuse device 10. When a dry type of fuse, such as shown in Triplett Patent No. 2,183,728, is used, it is not necessary to seal the fuse housing.

The fusible element 16 is arranged to melt on flow of predetermined current therethrough, such as on the occurrence of an overload or short circuit in the circuit in which the fuse device 10 is connected. As soon as the fusible element 16

melts all of the current flow is transferred to the strain element 17 which promptly parts and permits the terminal 15 to be retracted by the spring 20. An arc is formed between the terminals 14 and 15 which it is desired to extinguish as promptly as possible. This is accomplished, as is now well known, by elongating the arc and at the same time permitting the heat of the arc to evolve an arc extinguishing medium from an arc extinguishing material to sweep out the arc space so that at current zero on an alternating current circuit the arc space will be substantially nonconducting and the arc will not restrike.

In the embodiment of the invention disclosed in Figure 1 of the drawings, the arc extinguishing material comprises the liquid 12 which is directed into the arc space between the terminals 14 and 15 by the liquid director 19. Due to the heat of the arc the liquid is vaporized and it sweeps out the arc space within the arcing chamber 18. This is effective in promptly extinguishing the arc and preventing further current flow. This action results in a blast being created which flows outwardly through the upper end of the arcing chamber 18 along the paths indicated by the arrows 30 through openings 31 in the spider 27, and up into the extension 28. Now this blast comprises not only the gasified arc extinguishing liquid or the arc extinguishing medium in gaseous form but also contains metallic and non-metallic particles and compounds of the same which are formed as a result of the volatilization of the arc extinguishing liquid 12, fusible element 16, strain element 17 and portions of the terminals 14 and 15 which are subjected to the direct heat of the arc.

If the blast containing these ionized particles is discharged into the air, a flame results therein due to the oxidation of the particles which support combustion. While the remaining part of the blast is relatively harmless in so far as its electrical characteristics are concerned, this is not the case with the flame. As is well known, such a flame constitutes an electrical conductor and, as indicated hereinbefore, if it comes into proximity with one or more high voltage conductors it is likely to cause grounding of one or more of them or is likely to cause a short circuit between them. In a complicated switching structure it is sometimes extremely difficult to provide sufficient free space above the fuse devices so that any flame which is emitted therefrom cannot possibly cause these undesired results. Consequently, it is desirable to provide some means for preventing the formation of this flame.

In order to accomplish this desired end, advantage is taken of the fact that the particles which are contained in the blast are magnetic or possess magnetic properties or can be influenced or attracted by a magnetic field when they are about the temperature of the arc. To provide the magnetic field permanent magnets 32, 33, and 34, which, as shown in Figure 2, are of a horseshoe shape, are located in spaced apart relation by spacers 35 and 36 within the cylindrical extension 28. The blast resulting from the arc formed between the terminals 14 and 15 then passes upwardly around and between the projecting pole tips of the permanent magnets 32, 33 and 34 which are so positioned that the movement of the blast is substantially unhindered thereby. The metallic particles in the blast are removed therefrom by the permanent magnets and are deposited along the sides and the edges

thereof. When the resulting blast generates sufficient pressure within the extension 28 so as to blow the cap 29 off, substantially all of the ionized particles therein are removed therefrom by the permanent magnets 32, 33 and 34 so that the remaining un-ionized constituents of the blast are incapable of producing a flame when they encounter the air.

It will be noted that the permanent magnet 33 is positioned oppositely of the permanent magnets 32 and 34. This is to provide a somewhat more balanced design. Instead of this arrangement, the permanent magnets 32, 33 and 34 may occupy other relative positions as may be desired, a sufficient number being provided in order to insure removal or displacement of the maximum quantity of ionized particles that will be contained in the blast.

Any suitable magnet material for the permanent magnets 32, 33 and 34 can be employed. For example, various well known alloys of chromium and cobalt can be employed. Where space limitations constitute an important factor, permanent magnets of "Alnico" can be employed.

Referring now particularly to the embodiment of the invention shown in Figures 3A and 3B, it will be observed that the reference character 40 designates, generally, a combination of solid material and liquid fuse device of the type disclosed in the copending application of McMahon, Serial No. 239,263, filed November 7, 1938. This circuit interrupter or fuse device comprises a fuse tube or housing 41, preferably formed of glass, having corrugations 42 at its upper end for improving the electrical insulating properties thereof. At its lower end it is provided with a terminal 43 which is sealed in place by conventional means. The housing 41 is filled with a liquid 44, which is of the same character as the liquid 12 described hereinbefore, to the level indicated at 45.

The arc in the fuse device 40 is arranged to be drawn between a stationary terminal 46 that is carried by a metallic bridge 47 that is supported in a terminal 48 sealed to the upper end of the housing 41 and a relatively movable rod-like terminal 49, the lower end of which is secured in a spring and cable fastener 50. A coil tension spring 51 and a flexible conductor 52 are secured, as shown, to the spring and cable fastener 50 at their upper ends and at their lower ends they are secured to a similar spring and cable fastener 53 which is fastened to the lower terminal 49. It will be understood that the spring 51 serves to retract the rod-like terminal 49 and that the flexible conductor 52 serves to provide a low resistance current path between the rod-like terminal 49 and the terminal 43.

The terminals 46 and 49 are interconnected by a fusible element 54 which may be formed of silver and a strain element 55 which may be formed of a high strength alloy such as a nickel chromium alloy.

The rod-like terminal 49 is mounted for movement within a bore 58 in a mass of solid arc extinguishing material 59 that is arranged in the form of ring-like sections. It has been indicated in the application of McMahon that the solid arc extinguishing material 59 may be lithium fluoride. The solid arc extinguishing material 59 is suitably carried by an insulating sleeve 60, preferably formed of glass, that is mounted by a support member 61 from the terminal 48 at the upper end of the housing 41.

When the fusible and strain elements 54 and 55 are blown on the occurrence of an overload, an arc is formed between the terminals 46 and 49 and the latter terminal is released for movement through the bore 58 under the influence of the coil spring 51. An arc extinguishing medium, fluorine, if lithium fluoride is used for the solid arc extinguishing material 59, is evolved from the wall of the bore 58 due to the heat of the arc and a blast is formed for sweeping out the arc space between the terminals 46 and 49. Ordinarily the arc will be extinguished long before the rod-like terminal 49 reaches the lower end of the bore 58. The arrangement is such that the upper end of the rod-like terminal 49 will be drawn below the liquid level 45 so that an excellent dielectric is provided between the terminals 43 and 48 after the arc has been extinguished.

The upper end of the bore 58 opens into a throat or outflared opening 62 in a ring 63 of suitable insulating material. It is within the throat 62 and upper end of the bore 58 that the arc between the terminals 46 and 49 is formed on blowing of the fusible and strain elements 54 and 55.

As a result of the heat of the arc a blast is created for sweeping out the arc space between the terminals 46 and 49 in order to extinguish the arc. This blast is formed by the arc extinguishing medium that is evolved due to the heat of the arc from the solid arc extinguishing material 59. As before described, the blast that has swept out the arc space between the terminals 46 and 49 carries with it a quantity of metallic particles resulting from the volatilization of the fusible and strain elements 54 and 55 and portions of the terminals 46 and 49. If the blast with these metallic particles is discharged into the air, a conducting flame would be formed which is undesirable for the reasons set forth hereinbefore.

Again advantage is taken of the magnetic characteristics of the electrically charged particles in the blast in order to remove them from the same. It will be observed that the terminal 48 is provided with a cylindrical extension 64 that is closed at its upper end by a cap nut 65 and a vent cap 66, which is arranged to be blown off in the event that sufficient pressure is developed within the extension 64.

Mounted on the support member 61 is a magnet holder 67 which is generally cylindrical in form and is provided with pairs of openings 68 for receiving permanent magnets 69. The permanent magnets 69 are held in position in the openings 68 by means of tongues or lugs 70 which are bent inwardly to partially form the openings 68 and which serve to frictionally engage the permanent magnets 69. The construction and arrangement of the magnet holder 67 and the permanent magnets 69 are clearly shown in Figures 4 and 5 of the drawings.

The arrangement of the permanent magnets 69 is such that the passage of the blast through the cylindrical extension 64 is substantially unhindered. The permanent magnets 69 may be formed as hereinbefore described for the permanent magnets 32, 33 and 34. The magnets 69 are preferably arranged with opposite poles facing each other so that the lines of force are substantially perpendicular to the normal path of the exhaust gases passing through the chamber 64. In order to insure the effectiveness of the permanent magnets 69, all of the adjacent parts are formed of non-magnetic material such as brass or copper.

It will be understood that the arrangement of the magnets 69, shown in Figures 4 and 5 of the drawings, can be employed in lieu of the magnets 32, 33 and 34 shown in Figures 1 and 2 of the drawings. Also, they can be employed in the dry type fuse construction shown in Triplet Patent No. 2,183,728.

Tests under operating conditions using the fuse construction shown in Figure 1, with magnets arranged as illustrated in Figures 4 and 5 produced the following results:

1. The magnets were covered with a heavy deposit of carbon, finely divided metal and metallic chlorides.

2. The surfaces of walls in the chamber containing the magnets showed a white deposit consisting of metallic chlorides and underneath that a deposit of carbon, indicating that a selective action had occurred as the products of the arc were influenced by the magnetic field. Zinc chloride was one of the metallic chlorides found in a fairly large quantity. The zinc, derived from the brass forming the terminals combined with chlorine from the arc extinguishing liquid 12 to form the zinc chloride which, at the high temperature due to the heat of the arc, was strongly influenced by the magnetic field. The presence of carbon is due to the decomposition of this same arc extinguishing material.

In Figures 6 and 7 of the drawings another embodiment of the invention is shown. As there illustrated the reference character 74 designates, generally, a circuit interrupter that is generally similar to the circuit interrupter 40 described hereinbefore and illustrated in Figures 3A and 3B of the drawings. The circuit interrupter or fuse device 74 is provided with an insulating tube or housing 75 within which an arc is adapted to be formed between a stationary terminal 76 carried by a spider 77 on an upper terminal 78 and a relatively movable rod-like terminal 79 that is disposed for longitudinal movement within a bore 80 in a mass of solid arc extinguishing material 81 arranged in ring-like sections. The solid arc extinguishing material 81 is carried by means of a suitable tube or sleeve 82 which is supported by a support member 83 that is carried by the terminal 78. The terminals 76 and 79 are interconnected by a fusible element 84, preferably in the form of a silver wire and a strain element 85 that is preferably formed of high strength alloy wire, such as nickel chromium wire.

The creation of the blast for sweeping out the arc space between the terminals 76 and 79 in the fuse device 74 is substantially the same as previously described for the fuse device 40, shown in Figures 3A and 3B of the drawings. This blast will contain metallic particles which will support combustion on contact with the air and cause a conducting flame to be established which is undesirable for the reasons previously set forth.

The terminal 78 is provided with an integrally formed cylindrical extension 86 that is closed at its upper end by a cap nut 87 and a vent cap 88 that is arranged to be blown off when sufficient pressure is generated within the extension 86. The blast resulting from the circuit interruption and the arc formed between the terminals 76 and 79 flows upwardly along the paths indicated by the arrows 89 through openings 90 in the spider 77. It will be observed that, in the specific embodiment disclosed, four openings 90 are provided in the spider 77. Four arcuately

shaped permanent magnets 91 are provided immediately above the spider 77 and are so arranged that their ends project somewhat over the respective apertures 90, as is more clearly shown in Figure 7 of the drawings. A magnetic field is then created across the paths 89 of the blast and it is effective, as previously described, to attract or influence the particles which, at the temperature of the blast, possess magnetic properties.

It will be noted that several sets of arcuately shaped permanent magnets 91 are provided, the sets being positioned one above the other and spaced apart by spacer rings 92. The permanent magnets 91 making up the set immediately above the spider 77 and making up the set which constitutes the third set from the bottom are aligned. The permanent magnets 91 making up the remaining two sets are aligned but are shifted about 45° with respect to the other two sets in order to overlap the paths 89 of the blast as directed through the openings 90 in the spider 77.

In order to concentrate the magnetic fields of the permanent magnets 91 all of the parts associated therewith are formed of suitable relatively nonmagnetic material such as copper or brass.

In all of the embodiments of the invention disclosed, the arc will usually be extinguished by the time that the blast reaches the atmosphere. The only magnetic field that is present after the arc is extinguished then is that which is provided by the permanent magnets themselves. Even if the arc is not extinguished, the magnetic field surrounding it does not appreciably affect the action of the permanent magnet since the two fields are entirely independent and spaced apart.

Since certain further changes can be made in the foregoing constructions and different embodiments of the invention can be made without departing from the scope thereof, it is intended that all matter shown in the accompanying drawings and described hereinbefore shall be considered as illustrative and not in a limiting sense.

What is claimed as new is:

1. A circuit interrupter comprising, in combination, means between which an arc is formed resulting in a blast containing particles capable of being influenced by a magnetic field, and magnetic means positioned out of the influence of the magnetic field generated by current flow through said arc and along the path of said blast for controlling the movement of a substantial portion of said particles.

2. A circuit interrupter comprising, in combination, means between which an arc is formed resulting in a blast containing particles at high temperature possessing magnetic properties and supporting combustion on contact with air thereby forming a conducting flame, means confining said blast during a portion of its travel out of proximity with said arc and from contact with the air, and magnetic means for removing a substantial portion of said particles from said blast before the same contact the air thereby substantially preventing the formation of said flame.

3. A circuit interrupter comprising, in combination, a pair of terminals between which an arc is formed resulting in a blast containing particles possessing magnetic properties, means directing said blast endwise of said terminals, and means providing a magnetic field independent of the current flow through said arc and along the path of said blast for influencing the movement

of a substantial portion of said particles to remove them from said blast.

4. A circuit interrupter comprising, in combination, a pair of terminals between which an arc is formed resulting in a blast containing particles possessing magnetic properties at the temperature of the arc and supporting combustion on contact with air thereby forming a conducting flame, means directing said blast endwise of said terminals, means confining said blast during a portion of its travel out of proximity with said arc and from contact with the air, and means providing a magnetic field independent of the current flow through said arc in the space in which said blast is confined for influencing a substantial portion of said particles to remove them from said blast thereby substantially preventing the formation of said flame when said blast contacts the air.

5. A circuit interrupter comprising, in combination, a pair of terminals between which an arc is formed resulting in a blast containing particles possessing magnetic properties, means directing said blast endwise of said terminals, and permanent magnet means providing a magnetic field along the path of said blast for controlling the movement of a substantial portion of said particles to remove them from said blast.

6. A circuit interrupter comprising, in combination, a pair of terminals between which an arc is formed resulting in a blast containing metallic particles possessing magnetic properties at the temperature of the arc and supporting combustion on contact with air thereby forming a conducting flame, means directing said blast endwise of said terminals, means confining said blast during a portion of its travel out of proximity with said arc and from contact with the air, and permanent magnet means located in the space in which said blast is confined and arranged to permit substantially free movement of the same therethrough and adapted to provide magnetic flux for controlling the movement of a substantial portion of said metallic particles to remove them from said blast thereby leaving substantially none of them therein for contact with the air and preventing the formation of said flame.

7. A fuse comprising, in combination, a pair of terminals interconnected by metallic fusible means adapted to be ruptured on flow of predetermined current resulting in an arc between said terminals and a blast containing particles of said fusible means that possess magnetic properties, means directing said blast endwise of said terminals, and means providing a magnetic field independent of the current flow through said arc and along the path of said blast for controlling the movement of a substantial portion of said particles to remove them from said blast.

8. A fuse comprising, in combination, a pair of terminals interconnected by metallic fusible means adapted to be ruptured on flow of predetermined current resulting in an arc between said terminals and a blast containing particles of said fusible means possessing magnetic properties and supporting combustion on contact with air thereby forming a conducting flame, means directing said blast endwise of said terminals, means confining said blast during a portion of its travel out of proximity with said arc and from contact with the air, and means providing a magnetic field independent of the current flow through said arc in the space in which said blast is confined for influencing a substantial portion of said particles to remove them from said blast

thereby substantially preventing the formation of said flame when said blast contacts the air.

9. A fuse comprising, in combination, a pair of terminals interconnected by metallic fusible means adapted to be ruptured on flow of predetermined current resulting in an arc between said terminals and a blast containing particles of said fusible means that possess magnetic properties, means directing said blast endwise of said terminals, and permanent magnet means providing a magnetic field along the path of said blast for influencing a substantial portion of said particles to remove them from said blast.

10. A fuse comprising, in combination, a pair of terminals interconnected by metallic fusible means adapted to be ruptured on flow of predetermined current resulting in an arc between said terminals and a blast containing particles of said fusible means possessing magnetic properties and supporting combustion on contact with air thereby forming a conducting flame, means directing said blast endwise of said terminals, means confining said blast during a portion of its travel out of proximity with said arc and from contact with the air; and permanent magnet means located in the space in which said blast is confined and arranged to permit substantially free movement of the same therethrough and adapted to provide a magnetic field for influencing a substantial portion of said particles to remove them from said blast thereby leaving substantially none of them therein for contact with the air and preventing the formation of said flame.

11. A circuit interrupter comprising, in combination, a pair of relatively movable terminals between which an arc is established resulting in the formation of particles having magnetic properties, arc extinguishing material adapted to evolve an arc extinguishing medium due to the heat of the arc, means directing said arc extinguishing medium endwise of said terminals thereby creating a blast which sweeps away said particles from between said terminals, and means providing a magnetic field independent of the current flow through said arc and along the path of said blast for influencing a substantial portion of said particles to remove them from said last.

12. A circuit interrupter comprising, in combination, a pair of relatively movable terminals between which an arc is established resulting in the formation of metallic particles possessing magnetic properties at the temperature of the arc and supporting combustion on contact with air thereby forming a conducting flame, arc extinguishing material adapted to evolve an arc extinguishing medium due to the heat of the arc, means directing said arc extinguishing medium endwise of said terminals thereby creating a blast which sweeps away said metallic particles from between said terminals, means confining said blast out of proximity with said arc and from contact with the air, and means providing a magnetic field independent of the current flow through said arc in the space in which said blast is confined for influencing a substantial portion of said metallic particles to remove them from said blast thereby substantially preventing the formation of said flame when said blast contacts the air.

13. A fuse comprising, in combination, a pair of relatively movable terminals interconnected by one or more metallic fusible elements adapted to be blown on flow of predetermined current resulting in the formation of an arc between

said terminals accompanied by metallic particles of the fusible element or elements that possess magnetic properties, arc extinguishing material adapted to evolve an arc extinguishing medium due to the heat of the arc, means directing said arc extinguishing medium endwise of said terminals thereby creating a blast which sweeps away said metallic particles from between said terminals, and means providing a magnetic field independent of the current flow through said arc and along the path of said blast for influencing a substantial portion of said metallic particles to remove them from said blast.

14. A fuse comprising, in combination, a pair of relatively movable terminals interconnected by one or more metallic fusible elements adapted to be blown on flow of predetermined current resulting in the formation of an arc between said terminals accompanied by metallic particles of the fusible element or elements that possess magnetic properties and support combustion on contact with air thereby forming a conducting flame, arc extinguishing material adapted to evolve an arc extinguishing medium due to the heat of the arc, means directing said arc extinguishing medium endwise of said terminals thereby creating a blast which sweeps away said metallic particles from between said terminals, means confining said blast during a portion of its travel out of proximity with said arc and from contact with the air, and means providing a magnetic field independent of the current flow through said arc in the space in which said blast is confined for influencing a substantial portion of said metallic particles to remove them from said blast thereby substantially preventing the formation of said flame when said blast contacts the air.

15. A fuse comprising, in combination, a pair of terminals interconnected by metallic fusible means adapted to be ruptured on flow of predetermined current resulting in an arc between said terminals and a blast containing particles of said fusible means possessing magnetic properties and supporting combustion on contact with air thereby forming a conducting flame, means directing said blast endwise of said terminals, means confining said blast during a portion of its travel out of proximity with said arc and from contact with the air, and a plurality of permanent magnets in the space in which said blast is confined for influencing a substantial portion of said particles to remove them from said blast thereby substantially preventing the formation of said flame when said blast contacts the air.

16. A fuse comprising, in combination, a pair of relatively movable terminals interconnected by one or more metallic fusible elements adapted to be blown on flow of predetermined current resulting in the formation of an arc between said terminals accompanied by metallic particles of the fusible element or elements that possess magnetic properties and support combustion on contact with air thereby forming a conducting flame, arc extinguishing material adapted to evolve an arc extinguishing medium due to the heat of the arc, means directing said arc extinguishing medium endwise of said terminals thereby creating a blast which sweeps away said metallic particles from between said terminals, means confining said blast during a portion of its travel out of proximity with said arc and from contact with the air, and a plurality of permanent magnets in the space in which said

blast is confined for influencing a substantial portion of said particles to remove them from said blast thereby substantially preventing the formation of said flame when said blast contacts the air.

17. A fuse comprising, in combination, a pair of relatively movable terminals interconnected by one or more metallic fusible elements adapted to be blown on flow of predetermined current resulting in the formation of an arc between said terminals accompanied by metallic particles of the fusible element or elements that possess magnetic properties and support combustion on contact with air thereby forming a conducting flame, a liquid arc extinguishing material adapted to evolve a gaseous arc extinguishing medium due to the heat of the arc, means directing said gaseous arc extinguishing medium endwise of said terminals thereby creating a blast which sweeps away said metallic particles from between said terminals, means confining said blast during a portion of its travel out of proximity with said arc and from contact with the air, and means providing a magnetic field independent of the current flow through said arc in the space in which said blast is confined for influencing a substantial portion of said metallic particles to remove them from said blast thereby substantially preventing the formation of said flame when said blast contacts the air.

18. A fuse comprising, in combination, a pair of relatively movable terminals interconnected by one or more metallic fusible elements adapted to be blown on flow of predetermined current resulting in the formation of an arc between said terminals accompanied by metallic particles of the fusible element or elements that possess magnetic properties and support combustion on contact with air thereby forming a conducting flame, a solid arc extinguishing material adapted to evolve a gaseous arc extinguishing medium due to the heat of the arc, means directing said gaseous arc extinguishing medium endwise of said terminals thereby creating a blast which sweeps away said metallic particles from between said terminals, means confining said blast during a portion of its travel out of proximity with said arc and from contact with the air, and means providing a magnetic field independent of the current flow through said arc in the space in which said blast is confined for influencing a substantial portion of said metallic particles to remove them from said blast thereby substantially preventing the formation of said flame when said blast contacts the air.

19. A fuse comprising, in combination, a pair of terminals interconnected by metallic fusible means adapted to be ruptured on flow of predetermined current resulting in an arc between said terminals and a blast containing particles of said fusible means possessing magnetic properties and supporting combustion on contact with air thereby forming a conducting flame, means directing said blast endwise of said terminals, means confining said blast during a portion of its travel out of proximity with said arc and from contact with the air, and a plurality of horse-shoe shaped permanent magnets arranged in the space in which said blast is confined so as to permit relatively free flow of the same therethrough for influencing a substantial portion of said particles to remove them from said blast thereby substantially preventing the formation of said flame when said blast contacts the air.

20. A fuse comprising, in combination, a pair

of terminals interconnected by metallic fusible means adapted to be ruptured on flow of predetermined current resulting in an arc between said terminals and a blast containing particles of said fusible means possessing magnetic properties and supporting combustion on contact with air thereby forming a conducting flame, means directing said blast endwise of said terminals, means confining said blast during a portion of its travel out of proximity with said arc and from contact with the air, and a plurality of arcuately shaped spaced apart permanent magnets located in the space in which said blast is confined so as to permit relatively free flow of the same therethrough for influencing a substantial portion of said particles to remove them from said blast thereby substantially preventing the formation of said flame when said blast contacts the air.

21. A fuse comprising, in combination, a pair of terminals interconnected by metallic fusible means adapted to be ruptured on flow of predetermined current resulting in an arc between said terminals and a blast containing particles of said fusible means possessing magnetic properties and supporting combustion on contact with air thereby forming a conducting flame, means directing said blast endwise of said terminals, means confining said blast during a portion of its travel out of proximity with said arc and from contact with the air, and a plurality of spaced apart coaxial sets of arcuately shaped spaced apart permanent magnets located in the space in which said blast is confined so as to permit relatively free flow of the same therethrough for influencing a substantial portion of said particles to remove them from said blast thereby substantially preventing the formation of said flame when said blast contacts the air.

22. A fuse comprising, in combination, a pair of terminals interconnected by metallic fusible means adapted to be ruptured on flow of predetermined current resulting in an arc between said terminals and a blast containing particles of said fusible means possessing magnetic properties and supporting combustion on contact with air thereby forming a conducting flame, means directing said blast endwise of said terminals, means confining said blast during a portion of its travel out of proximity with said arc and from contact with the air, means directing said blast along a plurality of paths into the space in which it is confined, and means providing a

magnetic field along each of said paths for influencing a substantial portion of said particles to remove them from said blast thereby substantially preventing the formation of said flame when said blast contacts the air.

23. A fuse comprising, in combination, a pair of terminals interconnected by metallic fusible means adapted to be ruptured on flow of predetermined current resulting in an arc between said terminals and a blast containing particles of said fusible means possessing magnetic properties and supporting combustion on contact with air thereby forming a conducting flame, means directing said blast endwise of said terminals, means confining said blast during a portion of its travel out of proximity with said arc and from contact with the air, means directing said blast along a plurality of paths into the space in which it is confined, and a plurality of arcuately shaped circularly arranged spaced apart permanent magnets located in the space in which said blast is confined with the ends thereof along said paths for influencing a substantial portion of said particles to remove them from said blast thereby substantially preventing the formation of said flame when said blast contacts the air.

24. A circuit interrupter comprising, in combination, means between which an arc is formed resulting in a blast containing particles at high temperature possessing magnetic properties and supporting combustion on contact with air thereby forming a conducting flame, means confining said blast under pressure, magnetic means for removing a substantial portion of said particles from said blast while the same is confined under pressure, and means released at a predetermined pressure for allowing said blast to escape to the atmosphere after removal of said particles.

25. A circuit interrupter comprising, in combination, a pair of terminals between which an arc is formed resulting in a blast containing particles possessing magnetic properties, means directing said blast endwise of said terminals, means confining said blast under pressure, means providing a magnetic field independent of the current flow through said arc for removing a substantial portion of said particles from said blast while the same is confined under pressure, and means released at a predetermined pressure for allowing said blast to escape to the atmosphere after removal of said particles.

GEORGE F. McMAHON.
